UNITED STATES PATENT OFFICE.

ERNEST JOSEPH PERRY, OF BIRMINGHAM, ENGLAND.

SUSPENSION CHAIN FOR ELECTROLIERS AND FOR LIKE ELECTRICAL PURPOSES.

Application filed November 17, 1921. Serial No. 515,902.

To all whom it may concern:

Be it known that I, ERNEST JOSEPH PERRY, a subject of the Kingdom of Great Britain, residing at 68 Heathmill Lane, 5 Birmingham, England, have invented certain new and useful Improvements in or Relating to Suspension Chains for Electroliers and for like Electrical Purposes (for which I have filed application for 10 patent in Great Britain #30,685, October 30, 1920), of which the following is a specification.

This invention comprises certain improvements in or relating to suspension chains for electroliers and for like electrical purposes wherein a chain is employed to suspend a lamp or lamps and to convey the electric leads thereto.

More particularly the invention relates 20 to suspension chains of the type in which alternate links are of externally grooved formation so as to provide a means of protecting and partly enclosing and concealing the leads which are passed around 25 them on opposite sides for threading and crossing through the intermediate complementary links.

In this type of suspension chain the said intermediate links have ordinarily been of 30 a plain or ungrooved form affording only a limited protection for the leads.

The object of the present invention is to provide a suspension chain of this type in which the crossed and interthreaded 35 leads are more effectively protected and partly enclosed and concealed, and in which provision is made for more readily and economically lengthening or shortening the chain than has hitherto been possible in 40 this type of chain, and in which further said lengthening and shortening means is prevented when in use from causing uncoupling of the chain, the improved chain at the same time being stronger and more 45 flexible in construction, or superior ornamental effect, and of low cost to manufacture.

According to the present invention a suspension chain is furnished in which alternate links are of externally grooved formation 50 each having an inward embossment of substantially hemispherical conformation at one end, which embossment is cut through transversely to provide an open-ended link. 55 These open-ended inwardly embossed alternate links are assembled in conjunction

with an intermediate complementary series of closed links of internally grooved formation, the arrangement being such that whilst each complementary pair of links 60 can be readily opened and disconnected for lengthening or shortening purposes, the connection between said pair of links when assembled and in use is maintained in the closed position by engagement of the substantially hemispherical embossment of 65 one link within the internal groove of its complementary link, which internal groove at its point of engagement with said embossment has a substantially semi-circular 70 curvature in two directions at right angles, thereby providing both for the lateral closing action, and at the same time for a kind of pivotal ball-and-socket connection which is freely and flexibly movable in any direction. The internal grooves of the intermediate closed links further provide a means of more effectively enclosing and protecting the crossed and interthreaded 75 parts of the electric leads.

In order that this invention may be clearly understood and readily carried into practice, reference may be had to the appended explanatory sheet of drawings, 80 upon which:—

Figure 1 is a front elevation of a length of suspension chain in accordance with the invention and showing also the crossed and interthreaded electric leads.

Figure 2 is a side elevation of Figure 1. 90

Figure 3 is a sectional front elevation of the chain shown in Figures 1 and 2.

Figure 4 is a perspective view of the open-ended externally-grooved link shown in Figures 1 to 3. 95

Figure 5 is a perspective view of a length of suspension chain in a modified form.

Figure 6 is a perspective view of the open-ended externally-grooved link shown in Figure 5. 100

Figure 7 is a perspective view of a pair of links in which the complementary closed link is of a modified form.

Figure 8 is a perspective view of a length of suspension chain in a further modified form. 105

Figures 9 and 10 are perspective views of further modified forms of the complementary closed link.

In a convenient embodiment of the invention, Figures 1 to 4, alternate links *a* of the suspension chain are of seamless construc- 110

tion pressed or otherwise worked into an externally grooved formation of substantially semi-circular and externally concave cross-section, one end of said externally grooved link being further pressed by means of a suitable tool or die to form an inward embossment a^1 of substantially hemispherical conformation, which embossment a^1 is cut through transversely at a^2 to provide an 10 open-ended link. The intermediate complementary links b are likewise of seamless construction but are pressed into an internally grooved formation of substantially semi-circular and externally convex cross-section, the 15 alternate open-ended links a having a detachable and universally flexible locking connection to these intermediate complementary links b as hereinbefore described. c are the electric leads, the crossed and interthreaded 20 parts of which are partly enclosed and concealed and effectively protected by the external grooves of the alternate open-ended links a in cooperation with the internal grooves of the intermediate complementary 25 closed links b .

In a modified embodiment of the invention, Figures 5 and 6, the externally grooved alternate links a^3 are formed with an inward embossment a^4 at both ends, one only 30 of which embossments a^4 is cut through at a^3 to provide the open-ended link.

In a further modification, Figure 7, the internally grooved intermediate complementary links b are formed with a contracted 35 waist part b^1 which still more effectively en-

closes and protects the crossed and interthreaded parts of the electric leads.

In further modifications, Figures 8, 9 and 10, the intermediate complementary links b^4 , instead of being internally grooved, may be 40 of flat seamless construction with one (Figures 8 and 9) or both (Figure 10) of its semi-circular ends cut longitudinally to a short distance and expanded at b^5 to provide a terminal aperture or apertures b^6 into 45 which the embossment or embossments a^7 of the open-ended links are adapted to be passed, the expanded sides b^5 of said terminal aperture or apertures being suitably bent or twisted to provide a detachable locking 50 engagement with the embossment or embossments a^7 in a manner similar to that hereinbefore described.

What I claim as my invention and desire to secure by Letters Patent is:—

In a chain of the class described, a sheet metal link of concavo-convex cross section, arranged with the concave side outermost, and a sheet metal link of concavo-convex cross section, engaged with the first named 60 link and arranged with the concave side innermost, the first named link having a boss on its inner side at the point of engagement, said boss fitting in the concave side of the last named link and effecting a pivotal connection between the links.

In witness whereof I have hereunto set my hand.

ERNEST JOSEPH PERRY.
